UNITED STATES PATENT OFFICE.

OWEN DAVID LUCAS, OF WESTMINSTER, LONDON, ENGLAND.

CARBURETER FOR INTERNAL-COMBUSTION ENGINES.

1,150,782.

Specification of Letters Patent. Patented Aug. 17, 1915.

Application filed March 18, 1911. Serial No. 615,294.

To all whom it may concern:

Be it known that I, OWEN DAVID LUCAS, a subject of His Majesty King of England, residing at 39 Victoria street, Westminster, in the county of London, Kingdom of England, have invented certain new and useful Improvements in Carbureters for Internal-Combustion Engines, of which the following is a specification.

10 This invention has reference to improvements in carbureters for internal combustion engines and its object is to provide a means whereby proper quantities of air and liquid hydro-carbon are provided under all 15 conditions of working in the internal combustion engine.

The invention comprises two chambers in communication one with the other through one or more small orifices and into one of 20 the chambers the fuel passes by way of a jet, the other chamber communicating directly with the induction port of the engine. Both chambers are provided with air ports and there is provision for controlling the 25 effective sizes of these air ports for a purpose which will hereinafter appear.

The invention will be best understood from a consideration of the following detailed description taken in connection with 30 the accompanying drawings forming a part of this specification, with the understanding, however, that the arrangements indicated in the drawings are susceptible of various changes and modifications, where- 35 fore the invention is not limited to any exact conformity with the particular showing of the drawings.

In the drawings:—Figure 1 illustrates diagrammatically a carbureter with connections to an engine, and arranged in accordance with the present invention. Fig. 2 is a similar view showing a modified arrangement. Fig. 3 is a diagrammatic showing of 40 an arrangement of ports controlled by one 45 sliding throttle and indicating relative shapes of the ports to give the correct mixture for all positions of the throttle.

In the drawings there is indicated a chamber *a* in which the air and hydro-carbon 50 fuel become intermixed and which may, therefore, be termed the mixing chamber. This chamber *a* is provided with an air port *c*. At one side of the chamber *a* in the arrangement shown in Fig. 1, or centrally 55 located within the chamber *a*, as in Fig. 2, is another chamber *d* in the lower portion

of which there is located a jet *j*, wherefore the chamber *d* may for convenience be termed the jet chamber. Liquid hydro-carbon is directed to the jet *j* by any suitable 60 means, such as a constant level float chamber or its equivalent. The chamber *d* is provided with an air port *e*, while the chamber *a* is indicated as connected to the interior of the cylinder *h* of an engine by a 65 pipe *r* and the chamber *a* communicates with the chamber *d* through one or more small orifices, two such orifices *l* and *m* being indicated in the drawings, but it will be understood that a greater number of orifices 70 may be provided if desired.

In Fig. 1 the air ports *c* and *e* are simultaneously controlled by a common sliding throttle *f*, the arrangement being such that when one port is opened the other port is 75 closed. In Fig. 2 the air ports *c* and *e* are controlled by respective throttles *c'* and *e'* operated by interconnected levers in such a way that when one is opening the other is 80 closing.

No attempt is made to show in Fig. 1 the relative shape and size of the air ports *c* and *e*, while in Fig. 3 a shape and relative size of the two air ports is indicated, which shape has been found in practice to give 85 good results, but the shape of these ports may be varied in any suitable manner so long as there is maintained the desired relationship between the areas of the ports opened for a given displacement of the 90 throttle *f*. Furthermore, any suitable type of valve may be employed, whereby one port will be reduced in effective area as the other port is being enlarged in effective 95 area.

When the engine piston is moving on the suction stroke there is produced within the chamber *a* sub-atmospheric conditions, and sub-atmospheric conditions are also produced in the chamber *d* since the two chambers are in constant communication through the orifices *l* and *m*. The result of this action is that fuel is drawn into the chamber *d* through the jet *j* and from this chamber the fuel passes through the orifices in its wall to the chamber *a*, being ultimately drawn through the pipe *r* into the engine cylinder. Assuming that both air ports *c* and *e* are 100 open, the suction produced in the chamber *a* causes an inflow of air through the port *c* into the chamber *a* to there intermix with the fuel entering the chamber through the 105 port *e*. The air entering the chamber *a* through the port *c* will be drawn into the chamber *d* through the orifices *l* and *m* and will draw the fuel from the jet *j* into the chamber *d*. The fuel entering the chamber *d* will be drawn into the chamber *a* through the orifices in the wall of the chamber *d* and will intermix with the air entering the chamber *a* through the port *c*. The mixture of air and fuel will then be drawn through the pipe *r* into the engine cylinder. The air entering the chamber *a* through the port *e* will be drawn into the chamber *d* through the orifices *l* and *m* and will draw the fuel from the jet *j* into the chamber *d*. The fuel entering the chamber *d* will be drawn into the chamber *a* through the orifices in the wall of the chamber *d* and will intermix with the air entering the chamber *a* through the port *e*. The mixture of air and fuel will then be drawn through the pipe *r* into the engine cylinder.

orifices *l* and *m*, and the fuel entering the chamber *d* may also become intermixed to an extent with air entering the chamber *d* through the port *e*.

- 5 The air port of the chamber *a* is so situated that when it is closed the degree of vacuum in the mixing chamber *a* caused by the suction of the engine tends to increase, and therefore because the chamber *a* is in 10 communication with the chamber *d* through the orifices *l* and *m* the same condition would arise in the chamber *d* to increase the suction at the jet *j* were its tendency not counteracted by the opening of the port *e*, 15 which may, therefore, be termed the jet controlling port, as the port *c* which may be termed the air port, is closed, and, of course, the contrary action takes place when the air port *c* is opened and the jet controlling port 20 *e* is closed. The action of the air port *c* and its throttle on the jet is opposite to that in which a throttle operates when it is placed, as is customary, in the induction pipe between the jet and the engine.
- 25 By the present invention proper quantities of air and hydro-carbon are under all conditions of running delivered to the engine. To increase the amount of fuel the jet controlling port *e* is moved toward the closed 30 position, wherefore the action of suction is more pronounced in the chamber *d* and more fuel is drawn through the jet *j*. At the same time more air is admitted to the chamber *a* to compensate for the increased supply 35 of hydro-carbon fuel. When the port *c* is made effectively smaller the port *e* is made effectively larger, and consequently the action of suction on the jet *j* is correspondingly lessened, so that less fuel is delivered 40 into the chamber *d* and ultimately into the chamber *a* where a smaller amount of air is intermixed therewith.

The present invention has to do with the obtaining of correct proportions of air and 45 hydro-carbon, wherefore no means have been shown or described for atomizing and properly mixing the hydro-carbon with the air before it is introduced into the engine cylinder. Generally it will be necessary to associate some appropriate means for this purpose with the arrangement shown in the 50 drawings, but as any well known means may be employed for this purpose, it is not deemed necessary to illustrate and describe 55 the same. Since by the present invention the requisite proportions of air and hydro-carbon are provided at all times and under all conditions of running, the particular form of atomizer which may be employed is 60 of no especial moment.

In a carburetor constructed in accordance with the present invention there is no throttle between the mixing chamber and the engine and a throttle is placed on the atmospheric side of the main air inlet to con-

trol the air supply. The amount of hydro-carbon fuel required for any degree of opening of the main throttle is measured by controlling the amount of suction on the jet, thus actually measuring the hydro-carbon in 70 the liquid state before it is vaporized. While the part *j* has herein been termed a jet, this term is used for convenience of description and not in any sense limited to a finely graded orifice such as is commonly 75 used in carburetors.

The effect of the throttle on the atmospheric side of the mixing chamber is to cause an increase in the degree of vacuum therein as the throttle is closed, and to cause 80 a diminution of the degree of vacuum as the throttle is opened. Because the jet chamber is in constant communication with the mixing chamber through the small orifices, the degree of vacuum in the mixing chamber, if unmodified, would act directly on the jet or fuel inlet, thereby increasing the amount of fuel sucked in and proportioned to the closing movement of the main air throttle. The chamber *d*, however, communicates with the atmosphere through an air port which is opened as required to admit sufficient air to counteract the sub-atmospheric pressure within the chamber *d* to just that extent as will cause the sucking of the correct amount 95 of hydro-carbon into the chamber *d*. By properly proportioning the openings *c* and *e* and the throttling means therefor the openings may be simultaneously opened and closed in inverse order. Since air is used to 100 counteract the excess of suction on the fuel inlet, such air and the necessary hydro-carbon pass together through the fine orifices from the jet chamber *d* into the mixing chamber *a*, the effect being to atomize the 105 hydro-carbon and as the hydro-carbon spray so formed enters the mixing chamber where the degree of vacuum is always higher than that in the jet chamber, for the more the main air throttle is closed the higher is the 110 degree of vacuum, the already atomized hydro-carbon is thereby more readily converted into a true vapor or gas. The degree of vacuum in the mixing chamber is the least when the main air port *c* is wide open and then the greatest quantity of hydro-carbon is required. The size of the jet and jet chamber orifices are so adjusted 115 as to pass sufficient hydro-carbon with its atomizing air to give a correct mixture, when the main air port *c* is in the wide open position. Since the amount of hydro-carbon drawn into the carburetor is controlled by the amount of air admitted through the inlet *e* it follows that so long as the orifices are large enough the exact amount of hydro-carbon required is determined by the opening at the inlet *e*, wherefore the jet and jet chamber orifices may be standardized and require no further adjustment. For all 120 125 130

other positions of the main air throttle less air is admitted to the mixing chamber and consequently less hydro-carbon is required, and it follows that the suction in the jet chamber should never exceed that necessary when the main air port is wide open, but must decrease as the main air throttle is moved toward the closed position. Therefore, the more the main air port is closed 10 the more the jet chamber air port must be opened.

With any constant position of the main air throttle, and therefore also of the jet air throttle connected to it, the degree of 15 vacuum in the mixing chamber will vary as the speed of the engine, but any variation in sub-atmospheric pressure in the mixing chamber is as once communicated to the jet chamber and jet, and experience has shown 20 that the degree of vacuum in both chambers is correctly and automatically proportioned so as to give the correct mixture, and this arrangement may be made the more absolute by placing one or more of the orifices 25 between the jet chamber and the mixing chamber at a higher level than the others, that is, nearer the jet control air inlet, while the rest are nearly on a level with the top of the jet.

30 The adjustable throttling means described provides a control which may be used for ordinary governing purposes.

What is claimed is:—

1. A carbureter for internal combustion 35 engines, provided with separate chambers, one of which has means for direct communication with the engine and the other having means wholly therewithin for the introduction thereinto of hydrocarbon fluid, each 40 chamber being also provided with an air port opening directly to the atmosphere, and throttling means for the air ports movable to enlarge the effective area of the air port of one chamber simultaneously with the cutting 45 down of the effective area of the air port of the other chamber, or the reverse, and said chambers having constricted means of communication adjacent to the means for the introduction of hydrocarbon fluid and 50 remote therefrom.

2. A carbureter for internal combustion engines comprising two separate chambers each provided with an air port opening directly to the atmosphere, one of the chambers having an inlet for fuel wholly therewithin and at a point in the chamber remote from the air inlet thereof, and means for simultaneously varying the effective areas of the air ports in inverse relation one 55 to the other, said chambers having means of communication of relatively small area both adjacent to the fuel inlet means and to the air inlet of the fuel receiving chamber.

60 3. A carbureter for internal combustion engines having two separate chambers each

provided with an air port and one of the chambers having means wholly therewithin and individual thereto for the introduction of fuel, the chambers being in constant communication through orifices of relatively 70 small area and the air ports being of different sizes.

4. A carbureter for internal combustion engines having two separate chambers inter- 75 communicating through orifices of relatively small size, each chamber being provided with an air port and one of the chambers having means individual thereto and wholly inclosed therein for the introduction of liquid fuel.

5. A carbureter for internal combustion engines having two separate chambers inter- 80 communicating through orifices of relatively small size, both chambers being provided with air ports of larger size than the orifices, and one of the chambers having means individual thereto and wholly therewithin for the introduction of liquid fuel, the air ports being provided with means for regulating their effective area in inverse relation 85 to one with the other.

6. In a carbureter for internal combustion engines, means for delivering proper quantities of air and hydro-carbon under all conditions of running, consisting of two separate chambers, one provided with means wholly therewithin for the introduction of hydro-carbon liquid, and each chamber having an air port, the chambers being provided with one or more constantly open orifices of 90 relatively small area with respect to the air ports and constituting a means of inter- 95 communication between the chambers and throttling means for the air ports related thereto to enlarge the effective area of one air port while reducing the effective area of the other air port, and vice versa.

7. A carbureter for internal combustion engines having means for causing delivery 100 of proper quantities of air and hydro-carbon under all conditions of running of the engine, comprising two communicating chambers with one of the chambers provided with means for communication with the engine, and the other chamber being provided with means wholly therewithin for the introduction of liquid hydro-carbon, each chamber being provided with an air port, and throttling 105 means for the air ports constituting the sole throttling means for the carbureter.

8. In a carbureter for internal combustion engines, means for delivering proper quantities of air and hydro-carbon under all conditions of running, consisting of two separate chambers, one provided with means wholly therewithin for the introduction of hydro-carbon liquid and an air port at a point out of line with the travel of the hydro-carbon from one chamber to the other, and the other chamber also being provided with an air 110 115 120 125 130

port, the two chambers communicating one with the other through a plurality of small orifices located near the inlet means for the hydro-carbon, and also near the air ports, 5 and throttling means for the air ports related thereto to enlarge the effective area of one air port while reducing the effective area of the other air port, and vice versa.

9. A carbureter for internal combustion 10 engines having two separate chambers each provided with an air port, and one of the chambers having means individual thereto and wholly therewithin for the introduction of fuel, the chambers being separated by a 15 wall having a constantly open orifice therethrough of relatively small area and located near the means for the introduction of fuel, and an orifice of relatively small area located near the means for the introduction of 20 air into the chamber into which the fuel is introduced.

10. A carbureter for internal combustion engines provided with separate constantly 25 communicating chambers, one of which is provided with means for direct connection to the engine and the other with means wholly therewithin for the introduction of hydrocarbon fuel by suction, both chambers being provided with air ports opening directly 30 to the atmosphere, and throttling means therefor movable to enlarge the effec-

tive area of the air port of one chamber simultaneously with the cutting down of the effective area of the air port of the other chamber, or the reverse, the fuel inlet being 35 located at a relatively low point in the chamber containing it.

11. The method of supplying proper quantities of air and hydrocarbon fuel under all 40 conditions of running to a carbureter for an explosion engine, which consists in establishing, by the suction of the engine, subatmospheric pressure in separate communicating chambers, and in drawing thereby hydrocarbon fuel at a relatively low point in one 45 of the chambers, and introducing air directly from the atmosphere separately into the chambers, the atmospheric air entering the chamber initially receiving the fuel being in quantity inversely proportional to the 50 desired amount of fuel and the atmospheric air entering the other chamber being in quantity directly proportional to the desired amount of fuel.

In testimony whereof I have hereunto set 55 my hand in presence of two subscribing witnesses this day of 1911.

OWEN DAVID LUCAS.
